UNITED STATES PATENT OFFICE

HARRY LATZ, OF NEW YORK, N. Y., ASSIGNOR TO HARRY LATZ SERVICE, INC., OF NEW YORK, N. Y., A CORPORATION OF NEW YORK

DESIGN FOR AN ADVERTISING PAPER SHEET

Application filed October 7, 1930. Serial No. 37,177. Term of patent 3½ years.

To all whom it may concern:

Be it known that I, HARRY LATZ, a citizen of the United States, and resident of the borough of Manhattan, city, county, and State of New York, have invented a new, original, and ornamental Design for an Advertising Paper Sheet, of which the following is a specification, reference being had to the accompanying drawing, forming part hereof, which drawing shows a face view of an advertising paper sheet showing my design.

I claim:

The ornamental design for an advertising paper sheet, as shown.

HARRY LATZ.
